**DISPENSER FOR SHEET MATERIAL WOUND ON
A CORE HAVING ROTATABLE CAP MEANS
ENGAGING THE CORE**

James Dong, El Cerrito, and Frank Q. Hershey, Manhattan Beach, Calif., assignors to Kaiser Aluminum & Chemical Corporation, Oakland, Calif., a corporation of Delaware

Filed July 28, 1965, Ser. No. 475,399
13 Claims. (Cl. 225—23)

This application constitutes a continuation-in-part of our prior patent application Serial No. 346,714, filed February 24, 1964, and entitled "Dispenser for Sheet Material Wound on Hollow Core Having Rotatable Cap Means Engaging Interior of Core."

This invention relates to a combination merchandising and dispensing carton device or package and more particularly to a merchandising and dispensing package for enclosing a roll or web of sheet-like material, such as aluminum foil, which is adapted to be selectively dispensed therefrom and then severed into desired sectional lengths.

Accordingly, it is an object of this invention to provide an improved carton device or package of simple construction wherein novel means are employed for selectively dispensing portions of a web of sheet-like material disposed within said package.

This and other objects will become more apparent from a review of the following detailed description when considered in conjunction with the accompanying figures of the drawing, wherein:

FIG. 1 is an elevational view of a preferred embodiment of the dispensing device of the instant invention;

FIG. 2 is an enlarged broken longitudinal axial section of the device shown in FIG. 1 with parts thereof being broken away and other parts being shown in section for the sake of clarity, and with other parts being removed;

FIG. 3 is an elevational view of one element of the dispensing device;

FIG. 4 is a sectional view of the element shown in FIG. 3;

FIG. 5 is a sectional view of a modification of the part shown in FIGS. 3 and 4;

FIG. 6 is a broken longitudinal axial section similar to FIG. 2 of a further embodiment of the instant invention with certain parts being broken away and other parts being shown in section and with other parts being removed for the sake of clarity;

FIG. 7 is a broken longitudinal axial section similar to FIG. 6 of a further embodiment of the instant invention;

FIG. 8 is a broken longitudinal axial section similar to FIG. 6 and illustrates a modified form of one of the elements of the instant invention;

FIG. 9 is a cross-sectional view taken generally along line 9—9 of FIG. 6;

FIG. 10 is a cross-sectional view taken generally along line 10—10 of FIG. 7; and

FIG. 11 is a cross-sectional view taken generally along line 11—11 of FIG. 8.

It is to be understood that throughout the drawings like reference numbers will be used for like parts. With further reference to the drawings, and particularly FIGS. 1 and 2, the improved dispensing device or package 10 of the instant invention generally comprises an outer tube-like body or sleeve 12 preferably of a generally cylindrical configuration with open ends 14 and 16, and spaced longitudinal edges 18 and 20. Edge 20 can be provided with suitable serrations 22 or the like if desired. Sleeve 12 can be made of readily available material such

as a cardboard which in turn can be initially in the form of a flat blank that is subsequently formed into a tube-like body with the spaced longitudinal edges 18 and 20 defining a slot 28 after the open ends 14 and 16 of the sleeve have been closed by a pair of preferably identical core insertable caps 24 to be hereinafter further described in detail. The longitudinal slot 28 which extends between the spaced edges 18 and 20 is thus closed at the ends thereof by the caps 24 surrounding the ends 14 and 16 of the tube 12.

The roll or web of sheet-like material such as aluminum foil 30 that is to be dispensed is carried by a hollow core 34 (FIG. 2) disposed inside of the tube 12 of the container 10 in such a manner that the outer leading edge 32 of the foil 30 can extend beyond the slot 28 and over the one longitudinal edge 18 thereof in the fashion shown in FIG. 1. The hollow core 34 is of shorter length than the tube 12, as shown in FIG. 2. The longitudinal ends 36 of the core 34 are frictionally connected or operatively affixed to the caps 24 in a unique fashion such that rotation of either cap 24 can cause a corresponding rotation of the core 34 to thereby unwind the rolled foil 30 so that leading edge 32 thereof can be further extended beyond the slot 28 until the desired sectional length is obtained.

It is to be understood that the outer surface of core 34 will have an appropriate length of foil 30 or other web material wound thereon. The amount of material 30 carried by core 34 will be determined by the size of the packaging device and the amount of available space provided between the outer surface of the core and the inside surface of the tube-like body 12. In any event, the amount of material carried should be such as to avoid binding and crinkling of the material 30 against the inside surface of sleeve 12 during the dispensing of sections of the foil 30 through the slot of the sleeve 12. The length of foil 30 is wrapped around the core 34 in substantially tight folds. During dispensing when the desired sectional length of foil 30 has been projected through slot 28 the foil 30 located adjacent the edges 18 and 20 of the slot 28 is brought into contact with the serrations 22 to thereby sever the dispensed section from the roll of foil 30 and thereby re-establish a new leading edge 32 on the foil 30 still remaining wound about the core 34.

To enable the proper frictional connection of the core ends 36 to the caps 24 and thereby provide for rotation of the connected caps 24 and core 34 relative to the body 12, the caps 24 have a unique structure. As best shown in FIG. 4, each of the caps 24, which can be made from molded or press formed material such as any suitable plastic, is provided with an inwardly extending generally tapered or suitably configured boss 40 that can include a tapered outer annular surface 42 which is adapted to frictionally or operatively engage the inner surface 44 of the core at one of its ends 36. To further facilitate the frictional connection of the somewhat frusto-conical surface 42 of a cap 24 with the core 34, surface 42 can have a series of longitudinally extending splines or ribs generally indicated by lines 44' at the right-hand core end 36 as viewed in FIG. 2.

The outer surface 42 of boss 40 extends divergently outward from its juncture with inner surface 55 and terminates in an inwardly facing annular recess portion 46 of greater radial extent than surface 42. Recess 46 is bounded by boss 40 and an annular portion of the cap comprised of a radially extending wall 48 projecting from boss 40 and a cylindrical outer flange 50 generally disposed in spaced parallel relationship to the outer section of boss 40. The overall radial size or width of the recess should be such that a cap 24 can properly enclose its associated body end 14 or 16 as the case may be and at the same

time allow freedom of movement between either of the caps 24 and the tube 12. Thus there will always be a slight gap between the inside surface of flange 50 and the oppositely disposed surface of the tube end 14 or 16.

An annular shoulder 52 is advantageously provided intermediate the ends of the tapered boss 40. Shoulder 52 is adapted to abuttingly engage the radial end surface 54 of the core when the core 34 and an end cap 24 are assembled. The axial extent of the recess portion 46 beginning at the terminal end of the flange 50 and ending at the inner annular surface of the wall 48 and the location of the annular shoulder 52 on each cap 24 are so correlated so as to allow sufficient axial clearance space between each end 14 and 16 of the tube 12 and the associated inner annular surface of the wall 48 bounding the recess portion 46. In the absence of such a proper axial clearance space a binding engagement could occur between the various wall portions defining recess 46 of either cap 24 and the associated tube end 14 or 16.

The significance of establishing the proper spacial and clearance relationship between the various surfaces of boss 40 and wall portions of recess 46 is due to the fact that there cannot be any binding engagement of the tube ends with the recessed portion or pocket 46, whereby a jamming of the web carrying core could occur. Furthermore, the depth of the recess portion 46 of a cap 24 is such that when the cap 24 is attached to an end of tube 12, it will insure substantial alignment of the ends of the web 30 carried by the core 34 with the shoulder 52 of the cap and the slot 28 of the packaging device.

The innermost end of surface 42 of the tapered boss 40 advantageously folds back upon itself to form the inner wall 55 which along with wall 58 defines a closed end sleeve 56 inside of the boss 40. The sleeve 56 has a bottom planar wall 58 that can be disposed in substantial planar alignment with the outer peripheral wall 48 aforescribed. The purpose of this planar wall 58 is to provide an outer circular surface of sufficient area preferably for price marking when the dispensing device 10 is used as a merchandising carton. It is also to be observed that the caps 24 could be press formed of a metallic material, such as aluminum, instead of a plastic material as aforementioned.

FIG. 5 shows a slightly modified form of cap 59 wherein the like reference numbers correspond to the like parts of the aforescribed cap 24 in FIGS. 1-4. The inner end of the tapered boss 40 has been modified to include an inner radially extending apertured planar wall 60 formed integrally with the inner end of the tapered boss 40. The outer end of the tapered boss 40 is formed to include one planar wall 62 parallel to the apertured wall 60 and to extend radially outward to connect with the flange 50 instead of the two planar walls 48 and 58 of the cap 24 in FIGS. 1-4.

Another advantageous embodiment of the merchandising and dispensing device or package is shown in FIGS. 6 and 9 and will now be described in detail. This embodiment of the invention contemplates among other things that one end of the tube-like container body 12 can have a modified end cap 70 attached thereto. End cap 70 is rigidly secured such as by a tight friction fit or a suitable adhesive to package body 12 while being only loosely fitted with the end of the core 34 associated therewith. As with the aforescribed end caps or knobs of FIGS. 1-5, the modified end cap 70 can include an inwardly extending suitably configured boss or core bearing member 72, the outer wall 74 of which extends outwardly to connect with a radially and outwardly extending wall 76 of the cap 70. The inner end of boss 72 folds back upon itself to define an inner closed end sleeve 78 in a similar fashion as the aforescribed end caps 24 wherein the sleeve 78 has an inner wall 80 which terminates at a closed end 82. The outer wall 74 of the boss can, if desired, advantageously have an outwardly extending shoulder or stop 84 disposed intermediate its length which is

adapted to abuttingly engage the radial end surface 54 of the core 34 when it is operatively connected to the boss in the manner shown. It is to be understood, of course, that in assembling cap 70 and core 34, core 34 will be mounted on the boss 72 in such a fashion that the core 34 is free to rotate relative to the end cap 70 and its boss 72.

Affixation of cap 70 to an end 14 of the container body or casing 12 can be facilitated, if desired, by providing cap 70 with a pair of inwardly extending peripheral flanges 86 and 88 that are radially spaced from each other in such a fashion so as to permit the insertion therebetween of the associated end 14 of the container body 12. When the container body end 14 is inserted between the spaced flanges 86 and 88, it is positively engaged by the end cap 70 whereby no relative rotation can occur between the end cap 70 and the associated end 14 of the container body 12. To assure further positive engagement between body 12 and cap 70 it may be desirable to apply a suitable adhesive in a well-known manner to the spaced flanges 86 and 88 or to selected portions of the container body end insertable therebetween.

The other end 16 of the container body 12 in FIG. 6 can advantageously have an end cap 24 connected thereto in the same fashion as aforescribed in FIGS. 1-5. Further, the outer surface 42 of the boss 40 disposed in surface-to-surface engagement with the inner surface 36 of the core 34 can have a suitable adhesive applied thereto if desired. The portion of the boss in direct contact with the inner surface of the core need not be tapered but can be relatively straight and of such a dimension as to fit tightly and lockingly within the core. If desired, the boss 40 of the cap or core turning member 24 can have a core abutting shoulder 52. Thus, it will now be evident that in connection with the embodiment of FIGS. 6 and 9 the operator can merely grasp the packaging device 10 only by the end cap 70 while rotating the other end cap 24 in a predetermined direction in order to rotate the core and effect a selective dispensing or retraction of the web material 30 through the slot 28.

As shown in FIGS. 7 and 10, the package of FIG. 6 can be slightly modified whereby the end cap 24' is provided with a plurality of suitably spaced core engaging fingers 90 of the type indicated in FIGS. 7 and 10. The fingers 90 are separated by a series of inwardly extending grooves 92 formed in a longitudinal direction in the overall boss 40' such that the bottom of the grooves 92 preferably terminate adjacent the shoulder 52. When the cap 24' is made from a suitable material the fingers 90 can have a certain amount of resiliency which not only facilitates assembly between the boss 40' and the associated end of the core 34 but also provides for positive frictional surface-to-surface or operative engagement between the inner surface 36 of the associated core end and the outer surface 42' of the fingers 90.

Another modified configuration for an end cap that can be used with the package of FIG. 6 is shown in the end cap 24" of FIGS. 8 and 11. In this instance, end cap 24" can comprise an inwardly extending boss 94 which is advantageously formed in such a fashion so as to engage or encompass the outer surface of the associated core end and to be operatively connected thereto. To this end, the inner portion of the boss 94 can have an inner wall 96 opposed portions of which can, if desired, converge in the direction of the arrow A whereby wall 96 defines a sleeve having a closed outer end 98. In other words, the wall 96 constitutes a frustoconical section of a cone, the theoretical apex of which is located outside the packaging device 10 per se. The closed end 98 merges with the wall 48 of the recess 46. The outer wall surface 100 of the wall 96 of boss 94 extends outwardly to intersect the wall 48 so as to advantageously define the recess 46 aforescribed in connection with the other embodiments of the invention.

The inner surface of wall 96 of the boss 94 contacts the outer surface 36' of the core at one end thereof during assembly of core 34 and cap 24" whereby wall 96 is in operative or positive frictional surface-to-surface engagement with the associated end of the core 34. It is to be understood, of course, that the extent of engagement between surface 36' and the opposed surface of wall 96 will be such that the inner end of the boss 94 will not crinkle or seriously abrade the adjacent side edge of the material such as foil 30 folded around the outer surface of the core at the time the container body end 16 is freely disposed within the recess 46. Thus, the free edge of wall can be rounded off to prevent this. If desired an inwardly extending radial rib 97 can also be integrally formed on the wall surface 96 to abuttingly engage the end 54 of the core and thus limit the extent to which the core can be inserted within and locked to boss 94.

When using any of the embodiments of the instant invention illustrated in the drawings, rotation of a cap 24, 24', 24" or 59 as the case may be in the proper direction will cause a dispensing or retraction of the material 30 through the slot 28. When the desired sectional length of the foil 30 extends beyond the slot it is readily separated from the remainder of the web by passage across the serrations 22 of body edge 20. In the event that core 30 is rotated to such an extent such that the leading edge 32 of the foil 30 is withdrawn into the outer body 12 beyond the slot 28, the operator has only to rotate the core in either direction until the leading edge of the foil 30 realigns itself with the dispensing slot 28. The slot 28 is preferably of sufficient width between the edges 18 and 20 to enable the operator to easily grasp the leading edge 32 of the web 30 and redirect the leading edge 32 through slot 28.

We are aware that numerous dispensing containers have been contrived which are suitable for packaging and dispensing highly flexible sheet material such as paper and ribbon. In use, such devices ordinarily require that the free end of the sheet can only be dispensed by grasping and pulling the same from the container. This can result in a problem of wastage of material in that where an excess of material is pulled from the dispensing container no convenient means is provided as is provided by the core turning member of the instant invention for effecting a simple retraction of the excess material back into the container. Moreover, where the wound material to be dispensed is metal foil, dispensing solely by pulling on the foil material can produce objectionable wrinkles in the withdrawn portions of the sheet. It is an advantage of our construction that selected portions of the foil can be dispensed by rotation of a core turning member or end cap without having to rely solely on the manual pulling of the foil, thus obviating crinkling and objectionable wrinkles. At the same time we have provided a unique throw-away article or dispensing package which can be fully utilized and handled by the user without resort to special wall mounting equipment and the like.

It is also to be understood that it is with the contemplation of this invention to use certain advantageous features of one embodiment of the invention in conjunction with certain features of other embodiments. For example, the end cap 40' of FIG. 7 could be substituted for one of the end caps 24 of FIGS. 1-4.

An advantageous embodiment of the invention has been disclosed and described. It will be obvious that various changes and modifications may be made therein without departing from the spirit and scope thereof as defined by the following claims, wherein:

What is claimed is:

1. In a container device which is adapted to retain therein and dispense therefrom a web of sheet-like material the combination of an open ended tube-like body provided with spaced longitudinal edges, a hollow core rotat-

ably disposed in said body and having a web of sheet-like material to be dispensed wound therearound, a pair of end caps enclosing the ends of said body and forming in conjunction with the spaced edges of said body a longitudinal slot in said container device, at least one of said end caps including an inwardly extending tapered boss firmly and operatively connected at one end of said core with the inner surface thereof and outer wall means connected to and extending radially outward of the boss so as to define together with said boss an inwardly facing recess, the recess being of greater radial extent than the thickness of the associated tube-like body end, said end cap being firmly and operatively connected with the inner surface of the core in such a fashion that the cap has the associated tube-like body end disposed within its recess and the material wound within said tube-like body is disposed in relatively spaced as well as freely rotatable relationship with respect to the inner surface of said tube-like body whereby rotation of said end cap will cause a corresponding rotation of the core and a dispensing or retraction of a length of the material wound therearound through the slot in said container device.

2. In a container device for dispensing selected lengths of sheet-like material the combination of a hollow core having a web of sheet-like material wrapped therearound, a tube-like carton provided with open ends and spaced longitudinal edges for housing said core and the sheet-like material wrapped therearound and a pair of end caps enclosing the ends of said carton and forming in conjunction with the spaced edges of the carton a longitudinal slot in said container device, each of said end caps being provided with an inwardly extending tapered boss firmly and operatively connected to the inner surface of and at one end of said core and outer wall means connected to and extending radially outward of the boss so as to define together with said boss an inwardly facing recess, the recess of each end cap being greater in radial extent than the thickness of the associated carton end, said end caps being adapted to be mounted in frictional surface-to-surface engagement with the inner surface of the core at the open ends thereof and with a carton end being freely disposed within the recess of the end cap associated therewith, such that the mounted end caps act to hold said core and the material wound therearound within said carton and whereby rotation of either of said end caps will effect a corresponding rotation of said core and a dispensing or retraction of the material through the slot in said carton.

3. In a merchandising and dispensing device for a web of sheet-like material comprising the combination of a tube-like carton having open ends and spaced longitudinal edges a hollow core disposed within the carton and having a web of sheet-like material wrapped therearound and a pair of end caps enclosing the ends of said carton and forming in conjunction with said spaced edges of said carton a longitudinal slot in said merchandising and dispensing device whereby the free edge of the wrapped material is adapted to be dispensed through the slot of said device, each of said end caps including an inwardly extending tapered boss firmly and operatively connected with the inner surface of and at one end of said core and an annular portion connected to and extending radially outward of the tapered boss so as to define together with said boss an inwardly facing axial recess, the ends of said carton being of less thickness than the widths of the recesses so as to enable the ends of said carton to be freely disposed within the recesses of the respective caps, an annular shoulder disposed on the boss of each of said end caps intermediate the ends thereof for abutting the end of the core with which an individual cap is associated in such a fashion as to hold the carton ends disposed within the said recesses of the caps in axial spaced relationship relative to the annular portions of the caps and to maintain the edges of the material in proper alignment with the ends of the slot in the device whereby said end

caps upon being inserted within said core ends and disposed in rotatable relation to said carton ends can be rotated relative to said carton to effect a corresponding rotation of the core and a dispensing or retraction of the material on said core through the slot in said merchandising and dispensing device.

4. A dispensing device as set forth in claim 3 wherein the inwardly extending tapered boss of one of said caps is provided with a series of spaced ribs which are in frictional surface-to-surface engagement with the portion of the inside surface of the core associated therewith.

5. A device as set forth in claim 1 wherein one of the spaced edges of said tube-like body defining said slot is provided with a material cutting element.

6. In a packaging device which is adapted to retain therein and dispense therefrom a web of sheet-like material the combination of an open ended tube-like sleeve provided with spaced longitudinal edges, a core rotatably disposed in said tube-like sleeve and having a length of sheet-like web material to be dispensed wound therearound, a pair of end caps connected to the ends of said tube-like sleeve so as to form in conjunction with said spaced longitudinal edges of the sleeve a longitudinal slot in said packaging device, at least one of said end caps having an inwardly extending boss firmly and operatively connected to one end of said core and outer wall means connected to and extending radially outward of the boss so as to define together with said boss an inwardly facing recess, said recess being of greater radial extent than the thickness of the tube-like sleeve end associated therewith, said end cap being firmly and operatively connected to an end of the core in such a fashion that one end of the tube-like sleeve is freely disposed within the recess of the end cap while the core mounted within said tube-like sleeve is disposed in relatively spaced as well as freely rotatable relationship with respect to the inner surface of said sleeve whereby rotation of said end cap will cause a corresponding rotation of the core and a dispensing or retraction of a length of the material wound around the core through the slot in said packaging device.

7. In a packaging device as set forth in claim 6 wherein the other end cap is provided with a boss supportingly and slidably connected to the core and wall means connected to but spaced from said last mentioned boss, said last mentioned wall means also being rigidly affixed to the tube-like sleeve.

8. In a packaging device as set forth in claim 6 wherein the inwardly extending boss of said end cap is tapered and operatively connected to the core.

9. In a packaging device which is adapted to retain therein and dispense therefrom a web of sheet-like material the combination of an open ended tube-like sleeve provided with spaced longitudinal edges, a core rotatably disposed in said tube-like sleeve and having a length of sheet-like web material to be dispensed wound therearound, a pair of end caps closing off the ends of said sleeve and forming in conjunction with said spaced longitudinal edges of the sleeve a longitudinal slot in said packaging device, each of the end caps including an inwardly extending boss supportingly engaging the core, the inwardly extending boss of one of the end caps being comprised in part of a plurality of core engaging fingers certain surfaces of which are operatively connected to the core at the one end thereof, said last mentioned end cap further including outer wall means connected to and extending radially outwardly of the boss and the fingers thereof so as to define together with said boss an inwardly facing recess, said recess being of greater radial extent than the thickness of the tube-like sleeve end associated therewith, said last mentioned end cap being operatively and supportingly connected to the core in such a fashion that the one tube-like sleeve end is slidably disposed within the recess of the last mentioned end cap while the core mounted within said sleeve is disposed in relatively spaced as well as freely rotatable

75

relationship with respect to the inner surface of said tube-like sleeve whereby rotation of said last mentioned end cap will cause a corresponding rotation of the core and a dispensing or retraction of a length of the material wound about the core through the slot in said packaging device.

10. In a packaging device which is adapted to retain therein and dispense therefrom a web of sheet-like material the combination of an open ended tube-like sleeve provided with spaced longitudinal edges, a core rotatably disposed in said tube-like sleeve and having a length of sheet-like web material to be dispensed wound therearound, a pair of end caps closing off the ends of said tube-like sleeve and forming in conjunction with said spaced longitudinal edges of the sleeve a longitudinal slot in said packaging device, each of said end caps including an inwardly extending boss supportingly engaging the core, the inwardly extending boss of one end cap having an aperture within which one end of the core is fixedly disposed whereby the last mentioned boss is operatively connected to said core, said last mentioned cap further including outer wall means connected to and extending radially outward of the boss thereof so as to define together with said last mentioned boss an inwardly facing recess, said recess being of greater radial extent than the thickness of the tube-like sleeve end associated therewith, said last mentioned end cap also being operatively connected to the core in such a fashion that one tube-like sleeve end is slidably disposed within the recess of said last mentioned end cap while the core mounted within said tube-like sleeve is disposed in relatively spaced as well as freely rotatable relationship with respect to the inner surface of said tube-like sleeve whereby rotation of said last mentioned end cap will cause a corresponding rotation of the core and a dispensing or retraction of a length of the material wound about the core through the slot in said packaging device.

11. In a packaging device as set forth in claim 10 wherein the aperture of the boss is defined by an endless surface of frusto-conical configuration the theoretical apex of which is located outside of said packaging device.

12. In a packaging device which is adapted to retain therein and dispense therefrom a web of sheet-like material and comprising an open ended tube-like sleeve provided with spaced longitudinal edges, a hollow core rotatably disposed in said tube-like sleeve and having a length of sheet-like material to be dispensed wound therearound, a pair of end caps attached to and closing the ends of said tube-like sleeve and forming in conjunction with said spaced longitudinal edges of said sleeve a longitudinal slot in said packaging device and with each of said end caps being provided with a boss supportingly engaging the core, the improvement comprising one end cap operatively connected to the core and provided with outer wall means connected to and extending radially outward of the boss thereof so as to define with said last mentioned boss an inwardly facing recess, the radial extent of which recess is greater than the thickness of the tube-like sleeve end associated therewith, said last mentioned end cap being firmly and operatively connected to the core in such a fashion that the last mentioned end of the sleeve is freely and slidably disposed in the recess of said last mentioned cap while the core is disposed in relatively spaced as well as freely rotatable relationship with respect to the inner surface of said sleeve, whereby rotation of the last mentioned end cap will cause a corresponding rotation of the core and a dispensing or retraction of a length of the material wound about the core through the slot in said packaging device.

13. In a packaging device which is adapted to retain therein and dispense therefrom a web of sheet-like material the combination of a tube-like sleeve provided with spaced longitudinal edges, a core rotatably disposed in said tube-like sleeve and provided with a length of sheet-

like web material wound therearound which is adapted to be dispensed between said spaced edges of said sleeve, a core turning member provided with an inner portion operatively affixed to said core and an outer portion connected to said inner portion and extending radially outward of said core said outer portion having a recess within which an end of said sleeve is freely and slidably mounted whereby said sleeve will be retained within the recess of said turning member and be held in assembled relationship with respect to said core during rotation of said turning member and whereby rotation of said turning member will effect a rotation of the core and a dispensing or retraction of a length of the material wound about the core between the spaced edges of said tube-like sleeve.
